UNITED STATES PATENT OFFICE.

ALFRED E. TITUS, OF TRENTON, NEW JERSEY.

DOOR HINGE.

Application filed October 6, 1924. Serial No. 741,985.

To all whom it may concern:

Be it known that I, ALFRED E. TITUS, a citizen of the United States of America, residing at Trenton, in the county of Mercer and State of New Jersey, have invented certain new and useful Improvements in Door Hinges, of which the following is a specification.

The object of my invention is to provide a spring hinge for doors, more especially, the doors of refrigerators. Such hinge to be of a simple, practical and efficient construction that will insure the door being closed automatically with a tight joint in its frame; and with these and other objects in view, my invention consists of the parts and combination parts, as will be herein-after, more fully set forth.

In the drawings:

Figure 1 is a front elevation of a fragmentary part of a refrigerator and its door with my improved hinge thereon.

Figure 2 is a sectional view of the line 2—2 Figure 1 looking in the direction of the arrows.

Figure 3 is an enlarged detailed view.

Figure 4 is an enlarged perspective view.

Figure 5 is a sectional view on the line 5—5 Figure 2.

The reference numeral 1 designates the refrigerator and the door thereof, of any approved construction.

The long leaf 3 of the hinge is secured to the door while the short leaf 4 is secured to the refrigerator, as shown in the drawings. I secured a bracket 5 to the hinge leaf 4 by means of bolts 6, said bracket having its outer end yoked as at 7. To the leaf hinge 3 I secured a bracket 8, having the base plate 9, by means of the bolts 10, the bracket being, as shown in Figure 2, at right angles to base plate 9. While I have shown these brackets 5 and 8 as being screwed to the leaves of the hinge by means of bolts it will, of course, be understood that these brackets may be cast integral with the hinge.

In applying my invention to hinges already on the doors of refrigerators it, of course, is necessary that the brackets 5 and 8 be secured thereto by means of bolts, or rivets. The bracket 8 is provided with a circular opening, to be hereinafter referred to, from one edge of which extends a circular flange 11 forming with the walls of the circular opening an extended bearing to be herein-after referred to. Slots 12, diametrically

opposite each other, forms through the bracket 8, to be hereinafter referred to.

A rod 13 is pivoted at 14 in the yoke end 7 of the bracket 5 and extends through the circular opening 11 of the bracket 8, as shown in Figure 2, said rod having at one end an adjusted nut 15 adapted to be adjusted on the screw threads on one end of the rod 13, as shown in Figure 2. A stop 16 is rigidly secured on the rod 13 near its free end and is provided with arms 17 which are screw threaded into stop 16, as clearly shown in Figure 3. A coil spring 18 is secured around the rod 13 between the stop 16 and the adjusting nut 15 and is held between these two members under compression by reason of the fact that the arms 17 are prevented from passing through the slots 12 by the revoluble plate 19 against which they bear. This revoluble plate 19 is provided with elongated arcuated slots 20 in which set screws 21 are mounted, said set screws being screwed into the bracket 8 whereby the revoluble plate 19 is held, with its circular opening 22 in alinement with the circular opening in bracket 8. This revoluble plate 19 is provided with diametrically opposite slots 23 which, when the revoluble plate 19 is revolved by means of the handle 24 are adapted to register with the corresponding slots 12 of the bracket 8 where upon the arms 17 under the influence of the spring 18 passes through both sets of slots thereby relieving the compression of spring 18, whereby the door 2 will remain in any position in which it may be set. While the parts are in the position shown in Figure 2, the spring is under compression and the door will always be automatically forced by set spring to closed position.

After the desired compression has been placed on spring 18 the nut 15 is locked against movement by means of set screw 25. In order to cover the rod and spring to prevent the lodgment and accumulation of dust, etc., I cover them by means of the tube 26. In view of the above description, it is not believed that a detailed statement of the operation of the several parts is necessary.

As above pointed out my invention may be applied to existing hinges by simply bolting the brackets 5 and 8 to such hinges and mounting the other parts thereon. So in order to avail oneself of my invention it is not necessary to throw away the already un-supplied hinge.

I prefer to provide the hinge proper with antifriction washers 27.

While I am aware that some changes may be made in the details of construction and relative arrangement of parts without departing from the scope of the appended claims,

What I claim is:

1. In a hinge, the combination with a bracket secured to each leaf of the hinge, a rod pivotally secured at one end to one of said brackets and slidably mounted at its other end in the other of said brackets, a stop slidably mounted on said rod and adapted to engage one of said brackets, a spring on said rod, one end of which abuts said stop, a tension slide on the other end of said rod against which the other end of the spring abuts. A slot in one of said brackets, and means to move said stop to register with said slot whereby the stop may move beyond its bracket and release the compression on the spring.

2. In a hinge of the character described, a bracket for use therewith having an opening therethrough and slots in the walls of said opening diametrically opposite each other, a plate revolvably mounted on said bracket and having a central opening therethrough the wall of which opening having diametrically opposite slots spaced equally with the slots in the bracket.

3. In a hinge, the combination with a bracket mounted on each leaf of the hinge, a rod pivotally secured to one of said brackets and at its other end slidably mounted in the other of said brackets, an adjustable tension nut mounted on the pivoted end portion of the rod, a stop fixedly secured to the other end portion of the rod, a coiled spring on said rod under compression between said nut and stop, a plate revolvably mounted on said bracket and stop, said bracket and plate having equally spaced and diametrically opposite slots which slots when in register per-

mit the stop to move beyond the bracket and release the compression of the spring.

4. In a hinge, the combination with a bracket mounted on each leaf of the hinge, a rod pivotally secured to one of said brackets and at its other end slidably mounted in the other of said brackets, an adjustable tension nut mounted on the pivoted end portion of the rod, a stop fixedly secured to the other end portion of the rod, a coiled spring on said rod under compression between said nut and stop, a plate revolvably mounted on said bracket and stop, said bracket and plate having equally spaced and diametrically opposite slots which slots when in register permit the stop to move beyond the bracket and release the compression of the spring and a casing for the rod spring nut and stop.

5. In a hinge, the combination with a bracket on each leaf of the hinge, a rod pivotally secured to the bracket on one of said leaves, and slidably mounted at its other end in the bracket of the other leaf, a coiled spring on said rod, diametrically opposite slots in the walls of the opening of the bracket with which the rod has a sliding relation, a stop adjustably fixed on said rod and diametrically opposite arms extending at right angles from said stop, and adapted to pass through the said slots, a plate revolvably mounted on the bracket with which the rod has a sliding relation and provided with an opening registering with the opening in the bracket, diametrically opposite slots in the walls of the opening in said plate and adapted to register with the slots in the opening of the bracket to permit the stop and its arms to pass through the openings in the bracket and revolvable plate, to release the tension on the spring, and a tension device on said rod to govern the tension on said spring.

In testimony whereof I affix my signature.

ALFRED E. TITUS.
